UNITED STATES PATENT OFFICE.

ZACHARY T. HALL, OF PHILADELPHIA, PENNSYLVANIA.

DESIGN FOR A KNOB.

SPECIFICATION forming part of Design No. 16,515, dated February 9, 1886.

Application filed September 10, 1885. Serial No. 176,746. Term of patent 7 years.

To all whom it may concern:

Be it known that I, ZACHARY T. HALL, a citizen of the United States, residing in the city and county of Philadelphia, State of Pennsylvania, have invented and produced a new and original Design for a Knob, of which the following is a specification, reference being had to the accompanying drawing, forming part thereof.

10 The leading feature of my design for a knob is a head or top having a flat top and base and a corrugated periphery, and a conical peak rising from the top of the said head, having a base smaller than said top, the apex of the peak being in line with the center of the head, and a curved neck, the diameter of which is 15 smaller than the diameter of the head.

A represents a knob, having a head, B, and a neck, C, and D a peak rising from the head.

The head B has a flat top and base and a corrugated periphery, as at B'. The neck C is curved, as shown, and where it joins the head B is smaller than the diameter of the said head. The apex of the peak D is in a line with the center of the head and neck. 20 25

I claim—

A design for a knob having a curved neck of smaller diameter than the head, a head having a flat top and a flat base and a corrugated periphery, and a conical peak having a base smaller than said top, the apex thereof being in line with the center of both the head and neck, all as shown and described. 30

Z. T. HALL.
